COMBINATION CHAIR AND HORIZONTAL SWING BAR UNIT

Norma Bigler Masterson, 1207 E. 15th St., Lombard, Ill.

Filed Sept. 17, 1964, Ser. No. 81,760

Term of patent 14 years

(Cl. D15—1)

FIG. 1 is a perspective view of a combination chair and horizontal swing bar unit embodying my new design;

FIG. 2 is a side elevational view thereof as seen from the left-hand side of FIG. 1;

FIG. 3 is a rear elevational view as seen from left rear side in FIGS. 1 and 2;

FIG. 4 is a top plan view as seen from the top of FIGS. 1, 2 and 3;

FIG. 5 is a side elevational view of the new combination chair and horizontal swing bar unit inverted 180° from the position in which it is shown in FIGS. 1, 2, 3 and 4;

FIG. 6 is an elevational view as seen from the left-hand side in FIG. 5; and

FIG. 7 is an elevational view as seen from the right-hand side in FIG. 5.

The essential features of my design reside in the right angular relation of front and rear supporting legs in chair position and the obtuse angular relation of front and rear supporting legs in the inverted horizontal swing bar position, substantially as shown.

I claim:

The ornamental design for a combination chair and horizontal swing bar unit, substantially as shown and described.
